UNITED STATES PATENT OFFICE.

LEO GALITZKI, JR., OF CHICAGO, ILLINOIS, ASSIGNOR TO LEO GALITZKI, SR., OF CHICAGO, ILLINOIS.

HAT-PRESS.

1,196,100.

Specification of Letters Patent. Patented Aug. 29, 1916.

Application filed July 29, 1915. Serial No. 42,507.

To all whom it may concern:

Be it known that I, LEO GALITZKI, Jr., a citizen of the United States, residing at Chicago, in the county of Cook and State of Illinois, have invented certain new and useful Improvements in Hat-Presses, of which the following is a specification.

My invention relates to improvements in hat presses, whereby to press or block hats.

One of the objects of my invention is to generally improve, simplify and cheapen the construction of presses of this character, to the end that they may easily and quickly be operated; that their cost of production may not be prohibitive; that the interior may be visibly presented to the operator when the press is open, and that the parts carrying the expanding die may thus be entirely removed and out of the way at the time when the operator is placing the hat in the shaping die.

Other and further objects of my invention will become readily apparent to persons skilled in the art from a consideration of the following description when taken in conjunction with the drawings wherein—

Figure 1 is a front elevation of the press and the stand upon which it is mounted. Fig. 2 is a side elevation of the press, with the legs broken away. Fig. 3 is a plan view. Fig. 4 is a central section taken through the press showing it open.

In all the views the same reference characters are employed to indicate similar parts. The press 5 is mounted upon a stand 6, the latter is composed of four vertical legs 7, and connecting rungs 8, made preferably of gas pipe, to hold the legs in separated positions. Each leg is, preferably, provided with a flange 9 to afford a better base upon which the stand may rest.

Secured to the two rear legs of the stand are angle bars 10 and 11, carrying at their upper ends a shaft 12, upon which is mounted a grooved rope pulley 13. The legs 7 are joined together at their top ends by angle bars 15 which afford a base upon which the press 5 rests.

The press proper is divided into two major parts; the fixed steam jacketed part 16, which rests upon the stand, and a pivoted movable part 17 which is pivoted to the fixed part as at 18 and which is lifted by a counter weight 19 through the instrumentality of the rope 20 which passes over

the pulley 13 and which is connected to the upper portion 17 of the press by an eye 21.

The upper hinged portion 16, of the press, is provided with a forwardly projecting nose 22 which has association with the pivoted latch member 23, pivoted to the lower portion 16, as at 24, and having a portion 25 projecting forwardly to overlie the nose 22 when manually moved by the handle 26. This latch holds the parts together and prevents their separation when pressure is applied in the process of forming the hat.

The base portion 16 of the press carries a fixed die 27 which determines the shape of the hat. The die 27 may be lined with a more or less flexible porous lining 28, such as felt or the like, into which the hat 29 is placed when it is to be blocked or pressed. The relatively thick portion 16 of the die is provided with a steam jacket 30 communicating with which is a steam pipe 31, which is controlled by a globe valve 32.

The open hinge portion 17 of the die is concaved on its under side to provide a fluid space 33. A diaphragm 34 of yielding material such as rubber, partly closes the cavity 33. It is, however, provided with an opening 35 near its center, its outside edges being included between a flange 36, of the part 17, and a removable ring 37, secured to the flange, as by bolts 38—38. A ring of felt 39, is placed between the diaphragm 34 and the ring 37 to protect the diaphragm. A hat-like die 40, made preferably of rubber, or other similar material has somewhat the shape of the hat to be pressed and is secured to the diaphragm 34, around the edges of the orifice 35, and is adapted to enter the hat when the part 17 is placed in contact with the thick part 16 of the press. A water compressing device 41 provided with a handle 42, of the usual type is connected with the cavity 33 in the upper portion 17 of the press, by means of a flexible conduit or hose 43. A pressure gage 44 communicates with the interior of the upper portion 17 of the press and indicates to the operator the amount of pressure that is being applied to the press.

To press a hat, substantially as hat 29 shown in the press in Fig. 4, it is only necessary to place the hat in position in the die 27, the press is then closed when the rubber, or other yielding form 40, will enter the hat. The latch 23 is then brought into

position shown in Fig. 2, when the two parts of the press will be tightly held together. The flange 37 has a rim 37' which enters a cavity 16' in the part 16. This 5 provides a tortuous passage for the water that may escape through the flange 34 and the die 35 and be contained between the two parts of the press and prevents its escape and at the same time it forms a guide way 10 to hold the two parts of the press in proper register while it is being operated.

When the two parts, 16 and 17 of the press, are brought together, steam having previously been admitted into the cavity 15 30 of the lower portion 16 of the press, water under pressure is now admitted into the cavity 33 of the upper portion of the press which forces the yielding die 30 into intimate contact with the hat 29 and causes 20 it to assume the shape or form indicated by the die 27.

When it is desired to remove the hat from the lower portion 16 of the press it is only necessary to throw the latch 23 over out of 25 engagement with the nose 22, as in the position shown in Fig. 4, when the counter-weight 19 will automatically raise the press into the position shown. When in this po-

sition every part of the press, as well as the contents, is presented to view and is freely 30 accessible and the press is capable of being opened and closed in much quicker time than presses of the ordinary construction.

Having described my invention, what I 35 claim is:—

In a hat press the combination of a base portion 16, having a central depression for a die and having an annular groove 16' in its boundary wall; a hinge portion 17 having a cavity 33; a diaphragm 34 overlying the 40 cavity, and carrying a die 40; a clamping ring 37 overlying the marginal edges of the diaphragm and having an integral rim 37' which enters the groove 16' when the press is closed to provide means to hold the dies 45 against relative lateral displacement and to prevent escape of steam or water from the interior of the press.

In testimony whereof I hereunto set my hand in the presence of two subscribing 50 witnesses.

LEO GALITZKI, JR.

In the presence of—

STANLEY W. COOK,
MARY F. ALLEN.
